UNITED STATES PATENT OFFICE.

JOHN M. GREINER, OF MONMOUTH, ILLINOIS.

DESIGN FOR A LEVER OF A CLOSURE FOR JARS.

SPECIFICATION forming part of Design No. 85,370, dated December 3, 1901.

Application filed September 25, 1901. Serial No. 76,579. Term of patent 14 years.

To all whom it may concern:

Be it known that I, JOHN M. GREINER, a citizen of the United States, residing in the city of Monmouth, in the county of Warren and 5 State of Illinois, have invented and produced a new and original Design for the Lever of a Closure for Jars, of which the following is a specification, reference being had to the accompanying drawings, which are made a part 10 thereof, and in which—

Figure 1 is an elevation of the lever embodying the new design. Fig. 2 is an elevation thereof viewed from a position ninety degrees removed from the view-point of Fig. 1. Fig. 15 3 is a plan view thereof.

The essential leading novel features of a lever of the new design are a substantially semi-circular part *a*, terminating in arms *b*, which extend vertically with respect to the general 20 plane of said part *a* and lie in the same vertical planes of the extremities thereof, as seen

in Figs. 1 and 2, said arms *b* in turn terminating in lateral projections *c*, which extend inward horizontally toward each other and in approximate alinement with each other, the 25 lever being provided with perforations *d* at the junctions of the part *a* with the arms *b*.

Minor features are the widened portions *e* at the junctions of the part *a* with the arms *b*, said widened portions being bounded within 30 the angles formed by the part *a* and the arms *b* by curved lines which merge with the surface of the part *a* and the arms *b*.

What I claim as new, and desire to secure by Letters Patent, is—

35 The design for the lever of a closure for jars, substantially as herein shown and described.

JOHN M. GREINER.
